FALL BOARD

Filed July 13, 1923

UNITED STATES PATENT OFFICE.

TOLBERT F. CHEEK, OF NEW YORK, N. Y., ASSIGNOR, BY MESNE ASSIGNMENTS, TO WELTE-MIGNON CORPORATION, OF NEW YORK, N. Y., A CORPORATION OF DELAWARE.

FALL BOARD.

Application filed July 13, 1923. Serial No. 651,345.

This invention relates to musical instruments and has particular relation to improvements in that part of the casings thereof, usually called "fall boards", which are provided to protect the key-board against dust and atmospheric influences, when the keys are not being operated in the playing of the instrument, and are movable to uncover the keys for operation of the latter.

10 The primary object of my invention is the provision of an improved fall board which will be easily operated and which will take up a minimum amount of space, will present a slightly appearance, in no wise detracting but rather enhancing the appearance of the instrument as a whole, when it is in the position in which it covers and protects the piano keys. This primary object, and others which will be apparent to those familiar with instrument case structure, including fall boards and the like, are obtained in the structure illustrated and presently described, which is characterized, in part, by the provision of a main or body part, hereinafter called "fall board", of substantially flat shape, which is supported to be movable forward and rearward, within an opening formed in the front of the case of the piano or other instrument, and over the key-board 25 of the latter, in a substantially horizontal plane, and which board has the under side of its outer portion formed with a recess to receive the complementary member of the protecting means for the key-board, hereinafter called "front board", when the latter is in its raised position, the said front board being hinged to the fall board into position to swing downward to close the front end of the key space when the keys are 30 to be covered and to be swung upward underneath the fall board and into said recess when the keys are to be uncovered. Sufficient freedom of movement is provided for the fall board to permit a limited swinging 35 movement of the same about its rear portion as an axis, when it is in its outer position, to enable the front board to be swung relatively to the fall board, when the latter is in its outer position, without requiring 40 an undue extent of protrusion of the latter with relation to the vertical plane of the front ends of the keys. Other characteristic features of the invention have relation to the provision of an automatically operative

fastening means which is wholly concealed 55 from view and which holds the front of the board in its raised position, in the recess in the undersurface of the fall board, against accidental displacement, and to the provision of finger openings which facilitate or render convenient the manual operation of freeing the front board from said fastening means when the front board is to be lowered.

Referring to the drawing, where I have illustrated a preferred embodiment of my invention,

Figure 1 is a fragmental cross sectional view of my invention as applied to a grand piano and showing the fall board in its outer 70 position,

Figure 2 is a view similar to Figure 1 but showing the fall board at its inner or open position,

Figure 3 is a fragmental front view of the 75 structure shown in Figure 1,

Figures 4 and 5 are detail cross sectional views of the fall board and front board and showing the structure at different cross sections.

10 designates a piano case, 11 the keys and 12 the fall board. At the front of the fall board is a front board 13 which is hingedly connected to the fall board 12 at 14 and is foldable into the recess 15.

At the sides of the case and to support the fall board 12 are suitable supports, as the supports 16, arranged to cause the fall board to travel in a substantially horizontal plane. The fall board is provided with suitable 90 bearing surfaces adjacent the supports 16 as shown at 17 in Figures 4 and 5. These bearing surfaces may be of felt or any suitable material and contact with the supports 16. Due to the soft texture of the felt, the 95 fall board is prevented from scratching the supports or being scratched thereby.

At the rear of the recess, suitable fastening means are provided as shown in Figure 4. A small plate 20, having a recess therein, is provided in the bottom of the front board 13. In position to register therewith and in the rear of the recess 15, is placed a small device 21 having a spring pressed ball 22 so arranged as to press the ball outwardly and to engage the recess in the plate 20. One or more of these securing means may be placed at any suitable place or places.

At one or more places in the length of the fall board, a cut away space 23, wide enough for several fingers to enter, is provided adjacent thereto, the front board 13 is cut 5 away at 24 to form with the cut away space 23, a finger engaging pocket. When the fall board is in its forward position, it may be lifted about its rear as a pivot. When lifted, there is sufficient space between the 10 fall board and keys to either fold the front board under, or reach under and into the space 23 and the cut away place 24, to release the front board to lower the same to the position shown in Figure 1.

15 When the front board is in the position shown in Figure 2, the ball 22 holds it in place. When the finger pulls downwardly on the front board, the ball is caused to disengage the recess in the plate 20, and the 20 front board may then drop to a vertical position.

When the front board is in the position shown in Figure 2, the fall board may be pushed to the rear through the transverse 25 slot left in the face board of the case above the key board, leaving the forward portion of the keys exposed for playing. When desired, the forward edge 25 of the fall board 12 may be engaged by the fingers and the fall board pulled forward to cover the keys. The front board may then be dropped to closing position as already described and the parts permitted to assume positions disclosed in Figure 1.

35 It will thus be seen that I have provided a fall board which takes up a minimum amount of space, yet is efficient to perform its function, simple of construction and neat in appearance.

40 While I have described an embodiment of my invention in detail, I desire to have it understood that I do not limit myself to the exact showing and that modifications and changes may be made without departing 45 from the spirit of my invention and within the scope of the appended claims.

Having described my invention, what I claim is:—

50 1. A casing for a musical instrument having a key board, the said casing including a face board provided with an opening of such size relatively to the key board of the instrument that a transverse slot will be provided above said key board, the casing also including a fall board and a front board, the fall board mounted to have movement bodily in a substantially horizontal plane above the key board and through said slot and having a substantially plane upper surface, and 55 said front board being hinged to the fall board adjacent the outer edge of the latter and to be foldable thereunder to lie above the key board in one position of the fall board.

60 2. A casing for a musical instrument hav-

ing a key board, the said casing including a face board having an opening of such size relatively to the key board that a transverse slot will be provided in its forward portion and above the key board, the casing also including a fall board and a front board, the fall board mounted to have movement bodily in a substantially horizontal plane above the key board through said slot and provided with a recess in its undersurface, and the 70 said front board being hinged to the fall board adjacent the outer edge of the latter and being foldable thereunder and to lie in said recess and above the key board in one position of the fall board.

3. A casing for a musical instrument having an opening in its forward portion and provided adjacent the opening with a fall board mounted to have movement bodily in a substantially horizontal plane within said 75 opening and capable when in its outer position to be movable pivotally about an axis at its rear end, and a front board hinged to the fall board adjacent the outer edge of the latter and foldable thereunder.

4. A casing for a musical instrument having an opening in its forward portion and provided with a key-board protector which is movable bodily in a substantially horizontal plane within said opening and comprises two complementary parts, namely, a fall board and a front board, the front board hingedly attached to the fall board and foldable thereagainst and the fall board having a depression to receive the front board when the latter is folded, and a fastening means for the front board when in its folded position, including a yieldable fastening element, normally protruding from one of said parts and a recess in the 100 other part, to receive the protruding portion of said element when the two parts are relatively in position to be fastened together.

5. A casing for a musical instrument having an opening in its forward portion and provided adjacent the opening with a fall board mounted to have movement bodily within said opening and in a substantially horizontal plane relatively thereto, a front board hinged to the fall board adjacent the 105 outer edge of the latter and foldable thereunder, and a spring-pressed fastening element positioned in the fall board and in the path of upward swinging movement of the front board and yieldable to the latter in said movement and operative to hold the front board releasably in its folded position.

6. A casing for a musical instrument having an opening in its forward portion, a fall board mounted to have movement bodily in a substantially horizontal plane within said opening and a front board carried by the fall board and foldable thereagainst, the fall board having a depression 110

whose area with relation to that of the front board is such that the latter when folded will lie substantially within the horizontal plane of the corresponding surface of the fall board.

7. A casing for a musical instrument having an opening in its forward portion, a fall board mounted to have movement bodily in a substantially horizontal plane within 10 said opening, and a front board carried by the fall board and foldable upwardly thereagainst, the fall board having a depression in its under surface to receive the front board and whose area with relation to that of the 15 front board is such that the latter when folded will lie substantially within the horizontal plane of the corresponding surface of the fall board.

8. A casing for a musical instrument having an opening in its forward portion and provided with a key-board protector mounted to have movement bodily in a substantially horizontal plane within said opening, and comprising two complementary parts, 25 namely, a fall board and a front board carried by the fall board and foldable thereagainst, the fall board having a depression to receive the front board when the latter is folded, and said protector having a finger 30 opening adjacent confronting portions of the fall board and front board.

9. A casing for a musical instrument having an opening in its forward portion and provided with a key-board protector which

is movable bodily in a substantially horizontal plane within said opening and comprises two complementary parts, namely, a fall board provided in its underside with a depression and a pivoted front board carried by the fall board and foldable upwardly 40 into said depression, the protector also having a fastening means including a spring pressed element carried by one of the parts and normally protruding from the same and yieldable to pressure imposed by engagement of the other part, the part unprovided with said element having a recess to receive said protruding portion when the front board is in folded condition.

10. A casing for a musical instrument having an opening in its forward portion, a fall board mounted to have movement bodily within said opening and in a substantially horizontal plane and provided with a depression in its undersurface, a pivotal front 55 board carried by the fall board and foldable upwardly into said depression, and a yieldable fastening element in the path of swinging movement of the front board, the front board having a recess to receive the forward 60 portion of the fastening element when the fall board is in its folded position, and said fall board and front board having confronting portions formed to provide a finger opening.

In testimony whereof I affix my signature.

TOLBERT F. CHEEK.
